(12) **United States Design Patent**
Lee

(10) **Patent No.:** US D593,938 S
(45) **Date of Patent:** ** Jun. 9, 2009

(54) **TIRE**

(75) Inventor: **Si On Lee**, Gwangju-si (KR)

D586,290 S * 2/2009 Behr et al. D12/588

(73) Assignee: **Kumho Tire Co., Inc.**, Gwangju-si (KR)

* cited by examiner

(**) Term: **14 Years**

Primary Examiner—Stacia Cadmus

(21) Appl. No.: **29/330,945**

(74) Attorney, Agent, or Firm—Maier & Maier, PLLC

(22) Filed: **Jan. 16, 2009**

(57) **CLAIM**

(30) **Foreign Application Priority Data**

Nov. 14, 2008 (KR) 30-2008-0049147

The ornamental design for a tire, as shown and described.

(51) **LOC (9) Cl.** 12-15
(52) **U.S. Cl.** **D12/588**

DESCRIPTION

(58) **Field of Classification Search** D12/568,
D12/581-603, 900-901; 152/209.1, 209.8-209.18,
152/209.25, 209.28

FIG. 1 is a top perspective view of a tire, showing my design;
FIG. 2 is a front view;

See application file for complete search history.

FIG. 3 is a rear view;

(56) **References Cited**

FIG. 4 is a left-side view;

U.S. PATENT DOCUMENTS

FIG. 5 is a right-side view;

D531,113 S * 10/2006 Dixon et al. D12/587
D555,582 S * 11/2007 Lee D12/588

FIG. 6 is a top view;

FIG. 7 is a bottom view;

FIG. 8 is a partially enlarged view; and,

FIG. 9 is a cross-sectional view along the line A—A in FIG.
8.
